UNITED STATES PATENT OFFICE

ALBERT C. KALK, OF CHICAGO, ILLINOIS, ASSIGNOR TO INVINCIBLE LAUNDRY EQUIPMENT COMPANY, A CORPORATION OF ILLINOIS

REVERSING MECHANISM FOR LAUNDRY DRIERS

Application filed August 23, 1926. Serial No. 131,020.

This invention relates to a reversing mechanism primarily designed for driers but susceptible for use in other machines.

It is an object of this invention to provide a reversing mechanism that will shift a set of belts at regular intervals, in which the reversing mechanism may be disconnected simultaneously with the act of bringing the parts to neutral position, and means for adjusting parts of the machine for varying the position of the belts.

The invention comprises the novel structure, and combination of parts hereinafter described, and more particularly pointed out and defined in the appended claims.

In the accompanying drawings which illustrate a preferred embodiment of this invention, and in which similar reference numerals refer to similar features in the different views:

Figure 1 is an end elevational view of a drying machine to which this invention is applied.

Figure 2 is a part elevational and part sectional view of the operating mechanism for such machine.

Figure 3 is a top plan view of the structure shown in Figure 2.

Figure 4 is a sectional view upon the line IV—IV of Figure 2.

Figure 5 is a fragmentary elevational view looking at the right hand side of Figure 4.

Figure 6 is a sectional view taken substantially upon the line VI—VI of Figure 4.

Figure 7 is a sectional view taken upon the line VII—VII of Figure 6.

Figure 8 is an enlarged sectional view taken substantially upon the line VIII—VIII of Figure 5.

Figure 9 is a sectional view taken upon the line IX—IX of Figure 1.

Figure 10 is a sectional view taken upon the line X—X of Figure 9.

Figure 11 is an enlarged fragmentary elevational view through a belt shifter.

Figure 12 is an elevational view of a modified form of supporting frame for the driving mechanism.

Figure 13 is a sectional view taken upon the line XIII—XIII of Figure 12.

Figure 14 is a view taken substantially upon the line XIV—XIV of Figure 12.

In the drawing there is shown a cylindrical drying machine comprising a cylinder 1, a gear 2, which is coaxially secured with respect to the cylinder, a pinion 3 for rotating said gear, and a belt drive for rotating said gear. It may be mentioned that the gear 3 is secured upon a shaft 4 upon which a pair of loose pulleys 5 and 6 are mounted with an intermediate pulley 7 which is fast upon said shaft. A crossed belt 8 is trained over the pulley 5 and a wider belt 9 is trained over the pulleys 6 and 7. It will be noted that the pulley 6 is wider than the pulley 5, to accommodate the wider belt 9. However, when the belt 9 is shifted upon the pulley 7, it will still overlap a portion of the pulley 6 as shown in dotted lines in Figure 2 for a purpose that will later appear. These belts are shown as extending downwardly and trained over a drum 10 which is operatively connected to a motor 11 by the gears 12 and 13. However, instead of driving the belts by the motor 11, they may extend upwardly as shown in Figure 12 for connection to a line shaft or the like.

A pair of similar belt shifters 14 and 15 are provided. Each belt shifter is provided with a belt guide 16 at one end, and an upwardly extending arm 17 at the other end. Each arm has an arcuate groove 18 which terminates in a lower vertical portion 19 (Figure 11) whereby a vertical shoulder 20 is provided for a purpose that will later appear. With reference to Figure 2, it will be noted that the arms 17 on the shifters 14 and 15 slope in opposite directions. The belt shifters 14 and 15 are adapted to be actuated by a segmental-shaped arm 21 best shown in Figure 2. Pins 22 extend in opposite directions from the lower corners of the arm 21 and engage the grooves 18 in the arms 17 of the shifter elements. The arm 21 is rigidly secured upon a shaft 23 journalled in a suitable casting or housing supported upon the frame of the machine. A bifurcated member 24 is loosely journalled upon the shaft 23 and the rear end 25 of this member is provided with a clutch face adapted for clutch-

ing engagement with a shiftable clutch element 26 which is secured in a bushing or plate 27 and is slidably keyed upon the shaft 23. The bifurcated member 24 is adapted to be oscillated by a crank or wrist pin 28 which is eccentrically mounted upon a disk 29 secured upon the upper end of a vertical shaft 30, journalled in the aforementioned casting and housed in a cylinder 31. A worm 32 is secured upon the lower end of the shaft 30, and this worm meshes with a worm gear 33 which is coaxially secured to the pulley 6 and rotates relatively to the shaft 4.

Obviously, when the shaft 30 is rotated, the pin or finger 28 will oscillate the bifurcated member 24 and rock the shaft 23, provided the same is clutched to the shaft. The rocking of the shaft 23 will oscillate the aforementioned arm 21 for shifting the belt shifters.

A coil spring 34 surrounds the shaft 23 and normally forces the clutch element 26 into engagement with the bifurcated member 24. Mechanism has, however, been provided for shifting the clutch member 26 to inoperative position and maintaining the same in such position. This mechanism consists of a pair of rods 35 best shown in Figure 6. The rods have reduced portions which extend through the clutch bushing 27; the shoulders at the ends of such reduced portions normally abutting the said clutch plate 27. The reduced ends of the rods are slidably supported in the end of the housing 36, and the other ends of said rods extend through the opposite end of said housing. In referring to Figure 8, it will be noted that the last mentioned ends of said rods 35 are rounded or convex for coaction with the sloping faces 37 of cam plates or members 38 which are secured upon the inner side of a vertical slide plate 39. Upon the outer side of the slide plate 39 there are a pair of spaced plates 40 (Fig. 5), the lower ends of which serve as shoulders for engaging a pair of pins 41 projecting from the inner lower corners of a triangular shaped neutral plate 42, which is secured upon the shaft 23. The slide plate 39 is suitably slotted to receive the shaft 23 and to provide for sufficient sliding movement. When the bifurcated member 24 is clutched to the shaft 23, the slide plate 39 will be in elevated position with the cam plate 38 above the rods 35, which will be under the cam surface 37. Now to stop the machine, the slide plate 39 may be pulled downwardly whereby the rods 35 will be forced back and the clutch element 26 carried into inoperative position. At the same time, the shoulders on the plates 40 will engage the pins 41 which may be in a plane oblique to the horizontal, and bring the same into a horizontal plane, thereby rotating the shaft 23 to its neutral position, as shown in Figures 4, 5 and 7. It will, of course, be

understood that before the machine can be started again, the slide plate 39 must be elevated for releasing the clutch and moving out of the operative cycle of the neutral plate.

Mechanism has been provided for operating the slide plate 39. To this end, two pairs of spaced pins or studs 43 extend from the slide plate 39 upon opposite sides of the slot therein. These pins provide a way for an operating wrist pin 44 which extends through a crank arm 45 secured upon a shaft 46 which is suitably journalled in the frame. The shaft 46 is provided with a bevel gear 47 (Figure 5) upon one end which meshes with a bevel gear 48 secured upon a shaft 49. The gears 48 and 47 are located in a box or housing 50 secured to a side frame member. The ends of the shafts 46 and 49 are journalled in the walls of this housing 50. From the housing 50, the shaft 49 extends across the end of the cylinder 1 and is journalled in a bearing 51 (Figure 9) confined between the walls 52 and 53 of a bearing box 54 secured upon the side of the frame. A small shaft 55 is slidably mounted in said bearing box and bearing 51 and normally contacts the shaft 49 which is provided with a flat portion 56 which normally cooperates with the shaft 55 for preventing rotation of said shaft 49. The shaft 55 is provided with a groove 57 which is normally in engagement with the shaft 49 so that the same may be rotated by the handle 58 which is fixed upon the end thereof. The shaft 55 carries a pinion 59 which may be shifted into mesh with the driving gear 2 of the cylinder when the shaft 55 is shifted into the position shown in Figure 9. In this position the shaft 55 may be rotated by its crank 60 for rotating the cylinder 1 to bring the door thereon to the proper position after the machine has been stopped. In this position the shaft 49 is locked against rotation.

In order to prevent undue swinging movement of the crank 60, a frictional retarder 61 is positioned beneath the shaft 55 in a suitable recess provided in the wall of the bearing box 54. As shown in Figure 10, this retarder is in the form of a slide having a dished-shaped recess 62 directly opposite the shaft 55, and a threaded end 63 upon which a nut 64 is threaded, that engages the side of the bearing. By rotating the nut 64 the slide may be adjusted to frictionally bind against the shaft 55 to apply a braking action to prevent too easy rotation of the shaft. It will, of course, be understood that this braking action is not sufficient to prevent manual rotation of the shaft.

Instead of driving the machine by a motor as shown it may be driven from a line shaft. In such case, it may be desired to extend the belts 8 and 9 at a suitable angle or one different than is possible in the described organi-

zation. For this reason, the frame for supporting the reversing mechanism is adjustably mounted as shown in Figures 12, 13 and 14. In referring to said figures, it will be noted that the side of the frame is provided with a bearing support 65 provided with an arcuate slot 66. The housing 50 is provided with a depending lug 67 which is adapted to be adjustably bolted to the slotted bearing 65 by means of a bolt 68 extending through said slot.

In referring to Figures 12 and 13, it will be observed that the cylindrical housing 31 that supports the housing for the reversing mechanism thereabove is secured to the gear housing 69 for the gear 32. The gear housing 69 surrounds the shaft 4 and is provided with a depending flange 70 which is adapted to be adjustably bolted or secured to a stationary support 71 provided with spaced arcuate slots 72 by means of bolts extending through said slots. It will be obvious that by loosening the bolts at the two slotted connections and at the slot 66, the reversing mechanism 25 may be tilted as desired.

The operation

In describing the operation of the reversing mechanism it will be assumed that the parts 30 are in inoperative position. The first step necessary to start the same consists in the rotation of the crank 58 for operating the rods 49 and 46 and the crank arm 45 connected to the shaft 46 whereby the slide plate 39 may be elevated for releasing the rods 35 whereby the spring 34 will automatically shift the clutch 26 into engagement with the bifurcated member 24.

Assuming that the belt 8 is on the loose pulley 5 and the belt 9 is on the loose pulley 6, which is connected to the worm gear 33, it will be obvious, if the motor is now started, that the shaft 30 will be driven, and through the instrumentality of the pin 28 and bifurcated member 24, the reversing shaft 23 will be oscillated. As the shaft 23 is thuswise oscillated, the arm 21 thereon will, of course, oscillate therewith and shift the belt shifters. The first operation, due to the fact that the belts are on the loose pulleys, will result in oscillating the arm 21 to the right as shown in Figure 2. As the arm moves to the right the right-hand roller 22 will travel up the arcuate slot 18 of the belt shifter 15 without moving the same. However, the roller 22 on the left-hand end of the arm will shift the belt shifter 14 and move the belt 8 upon the fast pulley 7 whereby rotation will be imparted to the shaft 4 and the gear 3 thereon for rotating the cylinder.

After a predetermined number of revolutions of the cylinder, the wrist pin 28 will become effective for oscillating the bifurcated member 24 in the opposite direction for rocking the arm 21 in the opposite direction

or to the left as viewed in Figure 2. As the arm 21 moves to the left it will first shift the belt shifter 14 for placing the belt 8 on the pulley 5; the right hand roller 22 traveling down the arcuate slot 18 of the shifter 15 while the shifter 14 is being thuswise moved. When the right-hand roller reaches the bottom of the arcuate slot it will shift the shifter 15 for shifting the belt 9 into the position shown in dotted line in Figure 2. During this movement of the arm 21, the left half roller will naturally ride up the arcuate slot in the arm 17 of the shifter 14 without moving the same. It will be noted that the belt 9, on account of its breadth, overlaps a part of the pulley 6 so that it will simultaneously drive the fast pulley 7 and the loose pulley 6 so that the reversing mechanism will always be operated.

Now, assume that it is desired to stop the reversing mechanism for any purpose. The operator merely grasps the crank 58 for rotating the shafts 49 and 46 for drawing the slide plate 39 downwardly. After the slide plate 39 moves downwardly it will engage the ends of the rods 35 and shift the same inwardly against the tension of the spring 34 and the clutch member 26 whereby the reversing mechanism ceases to function. When the slide plate 39 is moved downwardly, the pin 41, which has the highest elevation, will be engaged by the plate 40 thereabove, and swung downwardly until the other pin 41 is contacted by its plate 40, which will occur when the two pins 41 are in substantially horizontal plane. As the pins 41 are thuswise brought into a horizontal plane, the neutral plate 42, upon which they are mounted, will naturally be brought to its neutral position. Likewise, the shaft 23 and the reversing mechanism connected thereto will be brought to neutral position. When the shaft 49 is in neutral position, it will present its flat portion to the groove 57 of shaft 55 and the shaft 55 may be shifted for manually rotating the cylinder and when it has been thuswise shifted, the shaft 49 will be locked against rotation by the flat portion thereof engaging the shaft 55. On the other hand, when the shaft 55 is in inoperative position and the machine is power driven, the shaft 49 will be lodged in groove 57 of the shaft 55, and may be rotated, but shaft 55 will be locked against shifting movements since the flat portion of shaft 49 will not be directly above the groove 57. It will be necessary to rotate shaft 49 to throw out the clutch and bring shaft 23 to neutral position before said flat portion will be above the groove 57 for unlocking the shaft 55.

From the foregoing it will be appreciated that a novel form of reversing mechanism has been provided, a reversing mechanism that is particularly adapted for a belt drive or the like, and in which one belt is used for

continuously driving the reversing mechanism. It will also be appreciated that by making these supporting members for the housing of the reversing mechanism adjustable, it is possible to adjust the housing to different inclinations as may be desired.

I am aware that numerous details of construction may be varied through a wide range without departing from the principles of this invention, and I therefore do not purpose limiting the patent granted hereon, otherwise than necessitated by the prior art.

I claim as my invention:

1. In a reversing mechanism, a driving shaft, a fast pulley on said shaft, a loose pulley on each side of said fast pulley, a pair of belts trained over a pair of said pulleys, a shifter member for each belt, each shifter member having a recess, a rockable shaft, an arm on said shaft for engaging said shifter members, a bifurcated member on said shaft, a rotatable device for alternately actuating said bifurcated member in opposite directions, a shaft for supporting said rotatable device, and a connection between said last mentioned shaft and one of said loose pulleys.

2. In a reversing mechanism, a driving shaft, a pulley fast upon said shaft, a loose pulley on each side of said fast pulley, a pair of belts trained over a pair of said pulleys, a shifter element connected to each belt, each shifter element having a recess, a rockable arm having means engageable in said recesses, a shaft for supporting said arm, a bifurcated member on said arm, a rotatable device for actuating said bifurcated member, means including a clutch for operatively connecting said rotatable device and said second mentioned shaft, and manually operated means for simultaneously rocking said last mentioned shaft to neutral position and operating said clutch for disconnecting said rotatable device.

3. In a reversing mechanism, a driving shaft, a fast pulley on said shaft, a loose pulley on each side of said fast pulley, a pair of belts trained over said pulleys, one of said belts being wider than said fast pulley for overlapping one of said loose pulleys, a shifter element connected to each belt, each shifter element having a recess, a rockable device having means engageable in said recesses for actuating said shiftable elements, a shaft for supporting said rockable device, a bifurcated member on said shaft, a rotatable device for actuating said bifurcated member, a shaft for supporting the rotatable device, gearing between said shaft and said overlapped pulley, a clutch for connecting said second mentioned shaft and bifurcated member, and means for simultaneously rocking said second shaft to neutral position and releasing said clutch.

4. In a drying machine of the class described, a reversing mechanism comprising shiftable elements, an arm for successively

shifting said elements, a shaft for supporting said arm, driving mechanism for said shaft including a clutch, a member slidable with respect to said shaft, a connection between said member and clutch, and a connection between said member and shaft whereby the sliding movement of said member will rock said shaft to neutral position and simultaneously declutch said clutch.

5. In a belt shifter, shifter arms, a rockable shaft, a driven member on said shaft, a clutch for connecting said member and shaft, a controlling member upon said shaft for holding same in neutral position, sliding means acting on said controlling member for rotating said shaft to neutral position and means actuated by said sliding member for declutching said clutch.

6. In a drying machine, a reversing mechanism comprising shiftable elements, an arm for successively shifting said elements, a shaft for supporting said arm, driving means for said shaft, a clutch, a member slidable transversely of said shaft, rods operated by said member for disengaging said clutch, and a device on said shaft operated by said member for rotating said shaft to a predetermined position.

7. In a reversing mechanism for a drying machine, a shaft, means for operating said shaft including a clutch, a device upon said shaft, a slide movable transversely of said shaft for rotating said device to a predetermined position, and means controlled by the movements of said slide for controlling said clutch.

8. In a machine of the class described, a support having an arcuate slot, a shaft, a housing on said shaft having a lug, a bolt adjustably connecting said lug to said slot, a second shaft, a support therefor, and means providing an adjustable connection between said second shaft and support.

In testimony whereof I have hereunto subscribed my name.

ALBERT C. KALK.
